UNITED STATES PATENT OFFICE.

CHARLES F. KING, OF PAWTUCKET, RHODE ISLAND.

LINK CUFF-BUTTON.

SPECIFICATION forming part of Letters Patent No. 787,455, dated April 18, 1905.

Application filed April 12, 1904. Serial No. 202,725.

To all whom it may concern:

Be it known that I, CHARLES F. KING, a citizen of the United States of America, and a resident of Pawtucket, Rhode Island, have 5 invented certain new and useful Improvements in Link Cuff-Buttons, of which the following is a specification.

My invention relates to improvements in link cuff-buttons, and the purpose of my invention is to provide a link cuff-button that combines simplicity of construction with facility and security of adjustment. I accomplish these objects by the device shown in the accompanying drawings, in which—

15 Figure 1 is a side view, one member being shown in section; Figs. 2 and 3, perspective views of the two elements or members composing the button, and Figs. 4 and 5 are perspective views of a modification of my invention.

20 In Fig. 1, A represents the ornamental front of one member of the button, and B the ornamental front of the other member. a' is the post fixed to A. This post is provided 25 with a perforation a^2 . Communicating with this perforation a^2 and extending to the extremity a^4 of the post is the slot a^3 , which is a little narrower than the diameter of a^2 . The post a' at the extremity farthest from the 30 front A terminates in a species of socket-joint a^4 , with which socket-joint the slot a^3 communicates.

35 The member B is provided with a post of any suitable form terminating on its inner end in the ball b' . The relative size of b' and the perforation a^2 are such that b' readily passes through the same, and the post connecting b' with B is of such size as to slide easily in the slot a^3 .

40 In use the separate members A and B are inserted into the eyelets of the cuff. The extremity b' of B is inserted into the hole a^2 , as shown by the dotted lines in Fig. 1, and then drawn into the socket a^4 by means of the slot 45 a^3 . The member B cannot then be readily separated from A, and disengagement can

only be accomplished by bringing the post of B to a position approximately at right angles to a' , as shown in the dotted lines in Fig. 1.

Fig. 4 is a modification of my invention, 50 differing only in detail from that shown in Fig. 1.

In Fig. 4 the post a^5 is tubular and has the perforation a^2 , the slot a^3 , and the socket-joint a^4 . B in Fig. 4 is provided with a post 55 ending with the ball b' , the post contiguous to b' being reduced in diameter, as shown, to facilitate its insertion into the perforation a^2 and the socket a^4 and to insure its retention in the latter.

It is clear that instead of the ball b' a cross-bar of suitable form and size would work equally well with a slight modification of the shape of the perforation a^2 and the retaining-socket a^4 . 65

Having now described my invention, what I claim, and desire to secure by Letters Patent, is—

1. A link cuff-button composed of separable members one carrying a post having a 70 longitudinally-disposed slot with a perforation at one end and a socket at the other end, the bearing-surface of the socket being at an angle to the sides of the post, the other member carrying a post having an enlarged extremity adapted to pass through the perforation in said first-named post and to lodge in 75 said socket and having universal movement in the socket.

2. A link cuff-button composed of separable members, one carrying a rearwardly-projecting rigid post having a longitudinally-disposed slot with a perforation at one end and a socket at the other, the other member carrying a rearwardly-projecting rigid post 85 with a ball on the end, said ball being capable of entering the perforation and of lodging in the socket and having universal movement in the latter.

3. A link cuff-button composed of separable sections, one carrying a tubular post with 90 a slot on one side, said slot communicating at

its inner end with a perforation and at its outer end with a socket in the end of the post, and a second member carrying a post with an enlargement on its end, said enlargement being adapted to pass through the said perforation into the tubular post and to lodge in the socket.

Signed at Pawtucket, Rhode Island, this 8th day of April, 1904.

CHARLES F. KING.
